UNITED STATES PATENT OFFICE.

GEORGE KELNER, OF CLEVELAND, OHIO.

SPRING LUBRICATOR.

Application filed February 17, 1926. Serial No. 88,862.

My present invention has to do with means for lubricating vehicle springs, and it contemplates the provision of a simple and inexpensive spring lubricator adapted to contain a considerable amount of oil and to adequately feed the same to the leaves of a spring, and one which is susceptible of quick and easy application to a vehicle spring without the employment of skilled labor or tools other than an ordinary nut wrench.

To the attainment of the foregoing, the invention consists in the improvement as hereinafter described and definitely claimed.

In the accompanying drawings, forming part of this specification:—

Figure 1 is a view showing partly in longitudinal section and partly in side elevation the preferred embodiment of my invention as applied to a vehicle spring.

Figure 2 is a top plan view of the same.

Figure 3 is an enlarged transverse section, taken in the plane indicated by the line 3—3 of Figure 1, looking toward the right.

Similar numerals of reference designate corresponding parts in all of the views of the drawings.

The spring illustrated is made up in conventional manner of a plurality of superposed leaves 1, the uppermost leaf being shown as terminating at its end in an eye 2 in accordance with accepted practice.

My novel lubricator is illustrated as applied for use, and it will be noted that among other elements the lubricator comprises a receptacle 3, preferably, though not necessarily, of sheet metal. It will also be noted that the receptacle 3 is generally tapered in the direction of its length, and is closed at its comparatively large end by a transverse wall 4, and is also provided with a bottom wall 5 and side walls 6, the latter having inwardly directed longitudinal flanges 7 as shown in Figures 2 and 3. At 8 the receptacle 3 is provided with a filling conduit that is normally closed by a cap 9, Figure 1.

Embracing the end portion of the receptacle 3 and also embracing the spring are hangers 10 and 11, the said hangers being, of different sizes, so as to snugly receive and fit the large end and the small end, respectively of the receptacle 3. Each hanger has inwardly directed upper arms and upstanding apertured ears 12 at the inner ends of said arms, and my invention contemplates the

connection of said ears 12 through the medium of bolts 13 and nuts 14 or any other appropriate connecting devices.

Interposed between the flanges 7 and the uppermost leaf of the spring are gaskets or packing strips 15, preferably of corks, the function of which is to prevent leakage of oil or lubricant between the said flanges 7 and the uppermost leaf.

Disposed in the receptacle 3 and under the end portions of the spring leaves so as to be immersed in and saturated by oil and so as to feed oil to the end portions of the spring leaves is a wick or strip of absorbent material designated by 16. The outer end of the said wick 16 is interposed between and held by the edge of the end wall 4 of the receptacle 3 and one of the spring leaves, and it will be noted that the wick extends longitudinally through the receptacle 3 and under the end portions of the spring leaves to the point where the foremost or innermost portion of the wick is clamped and held between the upturned flange 17 on the bottom wall of the receptacle 3 and the opposed surface of one of the spring leaves. It will also be noticed that adjacent to its innermost end the wick 16 is provided with side portions 18, Figures 1 and 3, the said side portions being interposed between the edges of the spring leaves and the side walls of the receptacle 3 so as to serve the twofold function of supplying oil to the leaves and preventing leakage of oil from the inner end of the receptacle 3.

It will be noticed that when properly supplied with oil at intervals, my novel device may be depended upon to adequately lubricate the leaves of a vehicle spring; and it will also be noticed that while there is no liability of my novel device being casually displaced in practice, yet when necessity demands the device may be expeditiously and easily removed from a spring and this without the assistance of skilled labor or the employment of any tool other than an ordinary nut wrench.

It will further be noted that my novel device is simple and inexpensive in construction, and in general is well adapted to withstand the usage to which automobile appurtenances are ordinarily subjected.

Manifestly oil may be supplied to the interior of the receptacle 3 at intervals through the conduit arm 8, and this with but little effort or inconvenience.

I have entered into a detailed description of the construction and relative arrangement of the parts embraced in the present and preferred embodiment of my invention in order to impart a full, clear and exact understanding of the said embodiment. I do not desire, however, to be understood as limiting myself to the precise construction and arrangement of parts as disclosed, my invention being defined by my appended claims within the scope of which modifications in structure and in arrangement may be made without departure from my invention.

Having described my invention, what I claim and desire to secure by Letters Patent, is: —

1. A spring lubricator comprising a receptacle having a bottom, side walls rising from the bottom along its longitudinal edges, the upper edges of the side walls inclining longitudinally and provided with inwardly directed flanges, an end wall rising from one end edge of the bottom and along the taller end edges of the side walls and of a height slightly less than the taller ends of the side walls and having its upper extremities provided with an outwardly and upwardly directed flange, an end wall rising from the other end edge of the bottom along the shorter end edges of the side walls and being less in height than said shorter ends of the side walls and having its upper extremity provided with an outwardly and downwardly directed flange, a capillary element having its ends disposed over the outwardly directed flanges and its side edges disposed under the inwardly directed flanges, and means for suspending the receptacle below a

leaf spring to supply the capillary element to the under-surface thereof so that lubricant in the receptacle will splash against the capillary element to maintain the same saturated with the lubricant.

2. A spring lubricator including a receptacle having a bottom, side walls rising from the bottom along its longitudinal edges, the upper edges of the side walls inclining longitudinally and provided with inwardly directed flanges, an end wall rising from one end edge of the bottom and along the taller edges of the side walls and of a height slightly less than the taller ends of the side walls, an end wall rising from the other end edge of the bottom along the shorter end edges of the side walls and being less in height than said shorter ends of the side walls, a capillary element extending over the receptacle with its side edges under the flanges, and means for suspending the receptacle below a leaf spring with the capillary element applied to the under surface of said spring so that the lubricant in the receptacle will be splashed against the capillary element to maintain the same in saturated condition.

3. A spring lubricator including a receptacle, a capillary element extending over the receptacle, and means for suspending the receptacle below a leaf spring to apply the capillary element to the under-surface of the spring so that the lubricant in the receptacle will be splashed against the capillary element to maintain the same in a saturated condition.

In testimony whereof I affix my signature.

GEORGE KELNER.
